Inventor:
Gaston A. Bronder, per
Thomas S. Crane, Atty.

UNITED STATES PATENT OFFICE.

GASTON A. BRONDER, OF BROOKLYN, NEW YORK.

AUTOMATIC SUGAR-CANE-FEEDER REGULATOR.

1,259,828.

Specification of Letters Patent. Patented Mar. 19, 1918.

Application filed January 15, 1917. Serial No. 142,393.

To all whom it may concern:

Be it known that I, GASTON A. BRONDER, a citizen of the United States, residing at 1874 East 12th street, Brooklyn, in the 5 county of Kings and State of New York, have invented certain new and useful Improvements in Automatic Sugar-Cane-Feeder Regulators, fully described and represented in the following specification and 10 the accompanying drawings, forming a part of the same.

This invention provides a means of securing a regulated supply of sugar-cane or similar material to devices adapted to operate 15 upon such material; and is especially suited for feeding sugar-cane to crushing-rolls, so that the rolls may be subjected constantly to the same strain, and the juice may be extracted from the cane more uniformly.

It has long been common to employ a traveling platform or slatted conveyer to feed the cane to the crushing-rolls; but in practice, the cane is dumped from field-cars 25 directly upon the conveyer and in consequence a very uneven layer of the cane is produced, some parts of the layer being very thin and others very thick, the thickness varying in practice from six inches to 30 three feet.

The attempts heretofore made have not succeeded in automatically delivering the cane to the crushing-rolls in a layer of even thickness.

35 The present invention accomplishes the object by providing a pair of gage-wheels to bear separately upon the same line across the layer of cane, and at a considerable distance apart, the wheels being mounted to 40 independently rise and fall, and the mean of their independent movements being imparted to suitable means for varying the speed of the conveyer inversely to the mean thickness of the layer.

45 The invention is applicable to the regulation of any motor that may be employed for propelling the conveyer, and the nature of such means and the mode in which it is operated by the gage-wheels will be fully 50 understood by reference to the annexed drawing, in which Figure 1 is a side elevation of a conveyer with an engine for driving the same and a governor connected with the gage-wheels and controlled by their 55 oscillations.

Fig. 2 is a plan of the same; Fig. 3 an end view of the guide-box for the shaft of the gage-wheels; Fig. 4 a side view of the guide-box with the shaft and portion of one of the gage-wheels; Fig. 5 is a longitudinal section upon the middle line of Fig. 2; Fig. 6 is a cross section where hatched, on line 6—6 in Fig. 1; and Fig. 7 is a vertical section of a centrifugal governor adapted to coöperate with the gage-wheels. Fig. 8 shows the sleeve-connections enlarged.

a designates the slats of a conveyer carried by chains *b* which extend over sprocket-wheels *b'*.

The shaft *c* of these wheels is mounted 70 upon a frame *d* with a steam-engine *e*, and the crank-shaft of the engine is connected to the shaft *c* by cog-wheels *c'*.

The conveyer carries the cane upwardly to a sufficient height to be delivered into a 75 trough having a floor *f* and sides *f'*, the floor being inclined downwardly to deliver the cane automatically to the crushing-rolls.

The conveyer moves between side-walls *a'* which retain the cane *g* thereon.

As shown in Fig. 5, and by dotted lines in Fig. 1, the cane is distributed unequally upon the conveyer so that the layer may, in practice, vary from six inches to thirty-six inches in depth, and a uniform layer can 85 only be delivered into the trough *f*, *f'*, by varying the speed of the conveyer inversely to the thickness of the layer.

The thicker portions of the layer are thus carried slowly over the highest point of the 90 elevator and delivered gradually into the trough, and the thinner portions of the layer would be delivered from the conveyer more rapidly, and thus compensate for the deficiency of thickness by the increase in 95 speed of delivery.

The engine *e* is provided with the usual governor *h* to compensate for variations in steam-pressure, and would maintain the engine at a uniform speed, but I provide the 100 governor with a special attachment and connect such attachment to the gage-wheels *i*, which rest upon the same as it is propelled by the conveyer, and thus vary the governor's operation.

The gage-wheels are shown located over the highest point of the conveyer but may be at any other point, as the variations in the layer are the same as at such delivery point.

105

110

Two gage-wheels are employed, as shown in Figs. 2 and 6, and are placed at opposite ends of a shaft or axle *j*, the middle point of which is pivoted in the guide-box *k* by a bolt *k'* so that it may oscillate in a vertical plane, and permit the wheels to rise and fall independently of one another in accordance with the thickness of the layer beneath such wheels.

10 The guide-box is connected to a rocker-bar *l* by an arm consisting of two angle-bars *m*, such bars being attached to a plate *k''* upon the guide-box.

15 A crank-arm *n* is attached to the rocker-bar and connected by a rod *o* to a regulator-sleeve *p* upon the top of the governor *h*, as shown in Fig. 7.

20 The governor-balls are carried by and rotated around a spindle *q*, and a spiral-spring *r* is fitted upon the spindle between the movable collar *s* of the governor-balls and a pressing washer *t* which is actuated by the regulator-sleeve *p*. The collar *s* is shown connected in the usual manner, by rod *u*, 25 with a balanced valve *u'* which supplies the engine with steam, and any pressure of the washer *t* upon the spring *r* produces a resistance to the expansion of the governor-balls, and causes the valve to give more 30 steam to the engine than it would under the normal operation of the balls, and thus increases the speed of the engine and the conveyer connected therewith.

Such pressure upon the washer is exerted 35 by an upward pull upon the rocker-sleeve *p*, and such pull is produced directly by a lifting of the gage-wheels when any thicker portion of the cane passes beneath them.

40 The contrary effect is produced upon the governor when the gage-wheels are lowered by a thinner portion of the cane.

45 As the cane lies very unevenly upon the conveyer it may be a foot or more thicker near one wall of the conveyer than the other, and the two wheels are supported at a sufficient distance apart to be affected by such differences in the layer, so as to impart a vertical movement, to the pivot, which expresses a mean of their movements, and indicates the 50 mean thickness of the layer.

It is obvious that the same freedom of oscillation can be imparted to the wheel-shaft *j* if the guide-box were dispensed with, and the end of the arm *m* were provided with a 55 pivot equivalent to the bolt *k'*.

The only purpose of the guide-box is to steady and support the axle while permitting it to oscillate in accordance with the independent rise and fall of the wheels.

60 The mean of the wheels' movements which corresponds to the mean thickness of the layer, is constantly transferred to the rocker-bar *l* and from that bar to the means for varying the speed of the conveyer.

65 The gage-wheels are preferably made of

suitable weight so as to press down upon the loose stalks of the cane, and thereby indicate the true thickness of the layer.

The wheels in practice are spaced a distance apart equal to one-half the width of 70 the trough so as to gage the thickness of the layer upon the same transverse line at a material distance apart.

The edges of the wheels are preferably 75 roughened so as to be rotated by the cane.

The movements of the gage-wheels in indicating the average thickness of the layer as it passes beneath the wheels, may be imparted to any regulating device which will 80 secure the uniform delivery of the cane to the trough which feeds the crushing-rolls, and it is therefore immaterial whether steam or water-power be used, or an electric motor, as controls are known for all of these powers and can be so actuated by connection with 85 the gage-wheels as to vary the movement of the motor and the conveyer in the manner described.

The device which makes the governer subject to regulation by the gage-wheels is not 90 claimed specifically herein, and is made the subject of a separate application.

Aprons hinged at one end over a conveyer have been used to rest at the other end upon a variable layer of material and gage the 95 thickness of such layer; but it is obvious that such an apron extending over the entire breadth of the layer is affected always by the highest part of the layer, and does not furnish any independent means of gaging 100 the thickness of the layer at opposite edges of the conveyer, and does not measure the mean thickness of the layer or actuate the regulating device in accordance with such mean thickness.

105 My invention therefore effects results which cannot be secured by an apron or other instrumentality bearing upon the entire width of the layer.

It will be observed that my feed regulator 110 is not limited in its operation to the delivery of sugar-cane to crushing-rolls, but is applicable to feeding any variable layer of stock to the operating device.

Having thus set forth the nature of the 115 invention what is claimed herein is:

1. In a sugar cane feeder, the combination; with a conveyer and a motor for propelling the conveyer, of a feed-gage consisting of a pair of oscillating spaced gage-wheels above 120 said conveyer and adapted to bear on a layer of material thereon, means for supporting the wheels for independently rising and falling upon the said layer of material, and means actuated by the oscillation of the 125 wheels for varying the speed of the motor inversely to the mean thickness of the layer.

2. In a sugar cane feeder, the combination, with a conveyer and means for operating the said conveyer, of a shaft sustained trans- 130

versely over the conveyer and having gage-wheels upon its opposite ends, said shaft having a transverse pivot-support at the middle movable vertically, whereby the 5 wheels have independent vertical movement and means connected with the said pivot-support and with the conveyer operating means for varying the speed of the conveyer inversely to the mean thickness of the layer.

10 3. In a sugar cane feeder, the combination, with a conveyer and means for operating the said conveyer, of a rocker-bar journaled

transversely over the conveyer, an arm projected from the rocker-bar with a transverse guide-box upon its end, a shaft pivoted in 15 the guide-box and having gage-wheels rotatable upon its opposite ends, and means connected with the rocker-bar for varying the speed of the conveyer inversely to the mean thickness of the layer.

20 In testimony whereof I have hereunto set my hand.

GASTON A. BRONDER.
